SOUND REPRODUCER

Manrico Compare, Milan, Italy

Application January 18, 1940, Serial No. 314,540
In Great Britain January 13, 1939

8 Claims. (Cl. 179—110)

This invention relates to sound reproducers and loud speakers.

The manufacture of sound reproducers is now generally directed to the production of cone type electromagnetic or electrodynamic loud speakers, as these have been found to be preferable to other types. The cone type speaker, however, still presents several drawbacks as, for example, the necessity of associating with it a screen or "baffle," 5 without which the sound would be distorted to such an extent as to render the reproduction muffled and most disagreeable. The baffle has the function of separating the air pressure variations at the front of the cone from those at the back 10 thereof and vice versa, when the cone vibrates.

An efficient baffle should be calculated according to the acoustic gamma of wave length, but a baffle actually complying with theory would be too large for practical use. In actual practice the 20 size of the baffle is very much reduced in order to render feasible its application to commercial sound reproducers and radio receivers. This reduction of size is therefore a compromise between the fidelity of sound and speech reproduction and the practical size of baffle. Further a good cabinet, 25 for a sound reproducer cannot be designed without consideration of the loud speaker for which the cabinet itself must function as a baffle. The cone type speaker is also undesirable as it 30 projects sound in one direction only, whereas radiation or circular propagation is desired in many instances.

It is an object of the present invention to provide a new loud speaker which will overcome the 35 above mentioned difficulties by comprising a mechanically practical unit which will produce better results. In conformation, this loud speaker may comprise a spheroidal or curviform structure adapted to vibrate at sound frequencies and to 40 assume a swelling and subsiding at each vibration, the outer surface of which radiates sound in all directions. The air contained within the spheroid sections has no communication with the outer air, hence the elimination of a baffle or 45 screen as employed in the present day cabinet. Accordingly, the invention broadly comprises a sound reproducer substantially spheroidal in conformation and combined with sound modifying means. One form of this arrangement is characterized by adjacent curviform diaphragms, such as spheres, spheroids or sections of same, one of 50 which has the function of producing and emitting sound waves and the other the function of making said diaphragm aperiodic.

55 One of the features of the present invention

comprises the positioning of elements within the vibratory structure, which elements have the function of making the same perfectly aperiodic. The elasticity of the air contained inside the spheroid or sections of it, while allowing the 5 structure itself to expand and contract freely at all acoustical frequencies, also acts as a resilience to cause resonance at certain frequencies. It is therefore desirable to incorporate the damping elements which may consist of spongy materials, 10 labyrinths or other elements. The vibratory spheroid may be actuated by a moving coil, a moving armature, or by a piezo-electric system. The spherical speaker can be located in a recess of a cabinet or separated from it at will without 15 losing its acoustical characteristics. If the speaker is located in a parabolic recess, its position can be adjusted to give the desired diverging angle of sound propagation.

A constructional arrangement of a spheroidal 20 sound reproducer may comprise a number of segments forming corrugations or indentations which extend from the top to the bottom, the upper ends being held by screws to one end of a rod-like member. The dampers within the sphere 25 are preferably formed of spongy discs and are supported by said rod-like member. The lower part of the sphere may be free to move with a moving coil which, for instance, is actuated by an incoming variable electric current which 30 causes the expanding and contracting facilitated by the corrugations. It may also be arranged so that both polar ends of the vibrating structure are actuated simultaneously, thus producing a 35 more efficient and balanced system of sound reproducer. If the material of the structure is sufficiently elastic, the corrugations may be dispensed with. The moving coil with its core and spider support may be secured in any known manner.

40 Alternatively, a damper may comprise a spheroid shaped member placed within the sound reproducer, the two spheres being attached at their polar ends and having a space between their substantially concentric walls. The damper sphere 45 is provided with a large number of perforations which permits air to flow therethrough with a resistance and thereby produce a damping effect. The spheroidal reproducer may be actuated piezoelectrically by means of a suitable piezo-electric 50 substance placed between the two diaphragms and which may be applied as a coating or covering on the outside of the perforated internal sphere or to the inner surface of the external vibrating sphere. The vibration of the sphere will thereby 55

be effected through the intervening dielectric. A step-up transformer would be employed in this arrangement, the primary of which is connected to the source of current and the ends of the secondary to the piezo-electric diaphragm and the other diaphragm respectively, both diaphragms being formed of conductive material.

The invention both as to its organization and method of operation, together with additional objects and advantages, will best be understood from the following description of the specific embodiments when read in connection with the accompanying drawings, wherein like reference characters indicate like parts throughout:

15 Figure 1 is a view in elevation of a spheroidal sound reproducer embodying the present invention;

Figure 2 is a plan view of the member shown in Figure 1; and

20 Figures 3, 4, 5 and 6 are views in elevation of spheroidal sound reproducers embodying modifications of the present invention, portions of Figures 5 and 6 being broken away to show the interior structure thereof.

25 With specific reference to the drawings, Figure 1 shows a spheroid 10, the upper part or pole of which is fixed by a cap 12 and a screw 13 to a supporting rod 14. The lower part or pole of the spheroid 10 is free to move and is fixed 30 to a spider 15. Corrugations 11 extend longitudinally about said spheroid 10 from its poles. The spider 15 is mounted upon a moving coil 16 which causes the expanding and contracting or vibrating of the spheroid 10 as indicated by 5 the broken lines. This vibration is permitted and/or facilitated by the corrugations 11 as best shown in Figure 2. The moving coil 16 comprises a part of an electromagnet 23 and is mounted on a core 17 and connected with a source of electric energy by the leads 18 and 18'. The coil structure is contained within a support 19 to which the supporting rod 14 is fixed by a threaded extension 20 and a nut 21. Damping members 22, in the form of spongy discs, are positioned within the spheroid 10 and supported by 45 the rod 14.

The various elements of the structure may be changed to suit variable conditions as shown in Figure 3 wherein a semi-spheroidal sound reproducer 10 is provided with spiral corrugations 11' extending over the surface of the sphere and between its poles. In addition, the electromagnet 23 comprising the moving coil 16 may be positioned within the sphere and secured to the 55 inner end of the supporting rod 14'. Sound modifying means 24 may be positioned between the rod 14' and the electromagnet 23. The exterior end of the rod 14' may be secured to one pole of the spheroidal structure by a cap 12 and a 60 screw 13, and the electromagnet may be secured to a collar 25 which is fixed about the other pole of the spheroid.

The core 17 of the electromagnet 23 may extend through the collar 25 and be fixed to any 65 suitable supporting means. According to this arrangement the moving coil of the electromagnet 23, in responding to electric impulses, will move reciprocally back and forth upon the core 17 and cause the poles of the spheroid to expand and contract. The vibration of the poles 70 in this manner will cause the entire surface of the spheroid to vibrate accordingly and the spiral corrugations will cause a spiral movement of the wall of the sphere 10. It will be seen by the 75 drawing that the motivating means is positioned

substantially within the sphere and that the two poles will be simultaneously actuated.

Another form of sound modifying means may be associated with the sphere as best shown in Figure 4. According to this structure the sphere 5 and electromagnet may be arranged as heretofore described but the sound modifying means comprises a series of parallel baffle plates 26 circumventing the exterior of the spheroidal structure 10. These baffle plates 26 may extend radially with respect to the supporting rod 14 and be provided with openings 27 conforming to the formation of the wall of the spheroid 10, and arranged so that the edges of said openings 27 lie closely adjacent to the surface of said wall. 15 The baffle plates 26 may be mounted in any suitable manner as upon rods 28 supported by brackets 29 which may be secured to the housing of the electromagnet 23. These baffles 26 may be of any suitable form or shape but of course the 20 openings must be concentric with respect to the wall of the spheroid 10 so that they may function to compensate the low sound frequencies as is well known.

The damping means may assume various forms 25 and comprise various materials. As shown in Figures 5 and 6, for instance, a second spheroid 30 may be positioned within the sound reproducing spheroid 10. This spheroid 30 is provided with perforations 31 to permit the air to 30 pass in and out of the interior chamber and the exterior space between the two sphere walls. The passing of the air through the perforations 31 creates a resistance to the free flowing of the air and thereby sets up a damping effect. 35 If a relatively rigid inner sphere 30 is employed the outer sphere may be mounted directly upon it at their poles, as shown in Figure 5, the screw 13 being secured to the inner spheroid 30 at one pole and the vibrating means being secured to 40 said inner spheroid 30 at the opposite pole.

This type of structure also permits a modification in the vibrating means as shown in Figure 6. Instead of employing an electromagnet for vibrating the sound reproducing sphere it 45 may be actuated piezo-electrically. For instance, suitable piezo-electric material may be coated upon the inner wall of the spheroid 10', the outer wall of the damping spheroid 30' or otherwise positioned upon or between the concentric walls in 50 any suitable manner. A suitable method of coating piezo-electric material is disclosed in German Patent 476,506 issued to Siemens and Halske Akt.-Ges. May 22, 1929. This would require that the two concentric spheres be formed of an electric conducting material. The primary of a suitable step-up transformer 32 may be connected to a source of current and the secondary to the 55 spheres which form piezo-electric armatures. According to this arrangement the electric impulses will act upon the external vibrating sphere 60 through the dielectric 33.

The use of a piezo-electric activating means also permits structural modifications of the sound reproducer. For instance, a substantially spherical vibrating member 10' may be employed and supported at only one pole. Likewise, the entire damping spheroid 30' may also be substantially spherical and supported at only one pole. In other words, the two spheres may be supported 70 at one point adjacent the transformer means and the whole surface of the sphere 10' may thereby be employed to produce a vibrating effect as indicated by the broken lines.

Although certain specific embodiments of the

present invention have been shown and described, many modifications thereof are possible, and the present disclosure should be construed only in an illustrative sense. The present invention, 5 therefore, is not to be restricted except insofar as is necessitated by the prior art and by the spirit of the appended claims.

I claim:

1. A sound reproducing device comprising in 10 combination a hollow approximately spherical body adapted to be expanded and contracted to thereby produce sound waves, a support at one point of said body, means connected with said body to cause the contraction and expansion thereof, and sound modifying means positioned 15 within said body to modify the sound waves produced thereby.

2. A sound reproducing device comprising in 20 combination a hollow approximately spherical body adapted to be expanded and contracted to thereby produce sound waves, a support at one point of said body, means connected with said body to cause the contraction and expansion thereof, a second hollow approximately spherical 25 body positioned within said first mentioned body to modify the sound waves produced thereby and having a plurality of apertures therein.

3. A sound reproducing device comprising in 30 combination a hollow approximately spherical body adapted to be expanded and contracted to thereby produce sound waves, a support at one point or said body, a second hollow approximately spherical body positioned within said first mentioned body to modify the sound waves produced thereby having a plurality of apertures 35 therein, the walls of said two bodies being substantially parallelly spaced and formed of electrically conducting materials, and a piezo-electric substance positioned between said walls to cause the contraction and expansion of the outer spherical body.

4. A sound reproducing device comprising in 40 combination a hollow approximately spherical body, substantially the whole surface of which is adapted to be expanded and contracted to thereby produce sound waves, said body com-

prising a solid wall, a support at one point of 5 said body, means connected with said body to cause the contraction and expansion thereof, and corrugations in said body to facilitate said expansion and contraction.

5. A sound reproducing device comprising in 10 combination a hollow approximately spherical body adapted to be expanded and contracted to thereby produce sound waves, a support at one point of said body, operating means connected 15 with said body to cause the contraction and expansion thereof, and corrugations in said body to facilitate said expansion and contraction, said corrugations extending longitudinally about said body from the point at which said operating 20 means contacts said body.

6. A sound reproducing device comprising in 20 combination a hollow approximately spherical body adapted to be expanded and contracted to thereby produce sound waves, a support at one 25 point of said body, means connected with said body to cause the contraction and expansion thereof, said corrugations extending spirally about said body.

7. A sound reproducing device comprising in 25 combination a hollow approximately spherical body adapted to be expanded and contracted to thereby produce sound waves, a support fixed 30 at one point of said body and extending therethrough, means connected with said body to cause the contraction and expansion thereof, and sound modifying means positioned within said body to modify the sound waves produced thereby, said sound modifying means comprising a plurality of spaced discs mounted on said sup- 35 port.

8. A sound reproducing device comprising in 40 combination a hollow approximately spherical body adapted to be expanded and contracted to thereby produce sound waves, a support at one point of said body, piezo-electric means connected with said body to cause the contraction and expansion thereof, and sound modifying means positioned within said body to modify the sound waves produced thereby. 45

MANRICO COMPARE.
